WATER WHEEL.

APPLICATION FILED FEB. 4, 1905.

2 SHEETS—SHEET 2.

UNITED STATES PATENT OFFICE.

OBED HAND NORDSTROM, OF PUNXSUTAWNEY, PENNSYLVANIA.

WATER-WHEEL.

No. 806,990.

Specification of Letters Patent.

Patented Dec. 12, 1905.

Application filed February 4, 1905. Serial No. 244,109.

To all whom it may concern:

Be it known that I, OBED HAND NORDSTROM, a citizen of the United States, residing at Punxsutawney, in the county of Jefferson and

5 State of Pennsylvania, have invented certain new and useful Improvements in Water-Wheels, of which the following is a specification, reference being had therein to the accompanying drawings.

10 My invention relates to water-wheels, and more particularly to that class of turbine-wheels wherein the water operates upon a series of blades or buckets, one of the objects being to provide a device of the character de-
15 scribed wherein the water shall be conveyed against and upon said blades or buckets through a plurality of channels, each channel leading directly into the chamber in which the buckets are arranged and by reason of
20 which a number of streams of water will engage with said blades or buckets simultaneously.

A further object of my said invention is to procure a device of the character described in
25 which the water can be automatically turned on through a number of channels by operating the valve to one of the channels and whereby it may be turned off by the same means.

A further object of the invention is to provide a valve that may be also used as a cutting-blade and which acts as such when weeds, grass, or other growth comes in contact with said valve, thereby keeping the entrance thereto constantly free from such obstructions.

30 A still further object of the invention is to provide means to overcome the resistance offered by the valve sticking in the valve-seat and whereby the valve may easily be operated.

Further objects and advantages of the invention, as well as the structural features by means of which said objects are attained, will be made clear by an examination of the specification, taken in connection with the accompanying drawings, in which the same reference-numerals indicate corresponding portions throughout, and in which—

Figure 1 is a side elevation. Fig. 2 is a central vertical section. Fig. 3 is a detail of the wheel carrying the buckets. Fig. 4 is a detail elevation of one of the valves. Fig. 5 is a detail side elevation of the double cams at the top of the valves. Fig. 6 is a top plan. Fig. 7 is a horizontal section. Fig. 8 is a view showing the application of my device. Fig. 9 is a

detail elevation illustrating the adjustment of 55 the lower bearing of the main shaft, and Fig. 10 is a sectional view showing the ball-bearings between the double cams.

1 designates a frame in which is adjustably mounted a platform 2, supporting a shaft 3, 60 having an enlarged base 3', said shaft carrying the cylinder 4, which has secured thereto or formed integral therewith the bucket-blades 5, the lower ends of which are surrounded by a ring 6. The cylinder 4 is mounted on the 65 shaft 3 by means of the threads 7, which engage with corresponding threads in the cylinder. These threads are so formed that when the water engages with the bucket-blades the greater the force exerted thereon by reason 70 thereof the tighter the cylinder will become screwed upon the shaft. A ball-bearing 8 is interposed between the platform 2 and the lower end of the shaft 3, upon which the shaft is adapted to rotate.

75 8' designates openings in the platform 2 beneath the ball-bearings in order that sand which may accumulate in the races in which the balls are adapted to rotate may be washed out, leaving the races clear and unobstructed.

80 The water is given ingress to the bucket-blades at four points, and as the arrangement of parts by means of which the water is conducted to the blades is similar in each a description of one will suffice for all.

85 A gear-wheel 9 is loosely mounted upon the shaft 3, said gear-wheel being engaged by a cog-wheel section or segment 10, having a number of cogs thereon adapted to fit those upon said wheel 9. This cog-wheel section 90 10 is rigidly mounted on a shaft or stem 11, which has rigidly secured thereto or formed integral therewith a valve 12, having an opening 13 with sharp cutting edges 14, said valve being mounted to turn in a cylindrical valve-seat 15, having openings 16 to admit the water, which passes into a chute 17, where it is forced against the bucket-blades 5. These bucket-blades are cam-shaped, being narrow at the top and wide at the bottom and are covered by a plate 18, rigidly mounted on top of the cylinder 4 and which effectually holds the water within the chute. The peculiar shape of the chute 17 causes the water to form a wedge by means of which it is given an extra force, all of which is exerted against the bucket-blade, which being spiral in shape has also the weight of the water upon it, which

augments the force against it, and which weight necessarily increases as the water approaches the lower end of each bucket-blade, the volume of water being greater at the lower end than at the upper. The shaft or stem 11 turns in a plate 19, rigidly mounted on the frame 1 and having thereon a cam projection 20, engaging with a corresponding cam projection 21, rigidly mounted on said shaft or stem, the two constituting a double cam. Each of said cam projections 20 and 21 has an adjustably-mounted cam-ring 22 of any suitable material and held in place by the set-screws 23. Ball-bearings 24 are interposed between the cam-surfaces and are held in place by said cam-rings, the edges of which extend beyond the cam-surfaces 20 and 21, the balls traveling in a race in the cam-surfaces, as shown. The object of this last-described arrangement of parts is to provide means for slightly raising the valve 12 in turning it in order to lessen the strain caused by said valve sticking in the valve-seat as the valve is given a vertical movement simultaneous with the horizontal.

The shaft 3 is mounted at its upper end in roller-bearings 25 and turns in a casing of Babbitt metal 26 to avoid wear and at the same time to preserve precision in the operations of said shaft. The platform 2, carrying the ball-bearings 8, upon which said shaft 3 rotates, is adjustably mounted in a frame 27 by means of the set-screws 28. The object of this last-mentioned arrangement of parts is to provide a means for keeping the shaft true at all times, so that if any of the parts become worn and the shaft thereby becomes out of plumb it can be returned to a perfectly vertical position by said arrangement.

Connected with the main frame 1, in which my said device is mounted and which constitutes a part of it, is a box or flume 29, which surrounds the entire device and carries the water to all of the openings 16, so that it may be turned on at all points simultaneously.

In operation the valves are opened by means of a hand-wheel 30, mounted on one of the shafts 11, motion being imparted to the remainder of said shafts 11 by means of the gear-wheel 9, which engages with all of the cog-sections 10, as heretofore stated. When said valve 12 is opened, the water rushes in, as indicated by the arrows pointing to the opening, and comes in contact with the bucket-blades 5, as heretofore explained, and descends upon said bucket-blades and passes out, as indicated by the lower arrows in Fig. 1, into a flume 31.

Having thus described my said invention, what I claim as new, and desire to secure by Letters Patent of the United States, is—

1. A turbine water-wheel, comprising a vertical shaft, a water-motor mounted thereon, a gear-wheel loosely mounted on said shaft, a plurality of tapering valve-seats having ob-

long openings therein opposite each other, a tapering valve having an oblong opening therethrough rotatably mounted in each valve-seat, a valve-stem formed integral with each valve, a circular plate mounted above each valve-seat, a cam-ring rigidly mounted on the valve-stem, a second cam-ring formed integral with the top of said plate, ball-bearings interposed between the two cam-rings, adjustable cam-rings surrounding the fixed cam-rings and having extending edges to hold the ball-bearings in place, and cog-segments mounted on each valve-stem and engaging with a gear-wheel.

2. In a water-wheel, the combination, with a suitable frame, a vertical shaft mounted in said frame, a gear-wheel rotatably mounted on the shaft above the frame, a plurality of tapering valve-seats, each valve-seat having two oblong openings therein opposite each other, a plurality of valves corresponding in contour to the valve-seats and adapted to rotate therein, each valve having an oblong opening corresponding to the openings in said valve-seats, a valve-stem mounted on each valve by which the same is adapted to be actuated, a plate rigidly mounted over each valve and valve-seat and having a cam-ring formed integral therewith, or rigidly mounted thereon, said cam-ring and plate having an opening in which the valve-stem is adapted to rotate, a ring encircling the cam-ring, a second cam-ring rigidly mounted on each valve-stem, a ring encircling the second cam-ring, ball-bearings interposed between the cam-rings and held in place by the rings encircling them, a cog-segment rigidly mounted on each valve-stem and adapted to engage the gear-wheel, one cog-segment being adapted to operate the gear-wheel and thereby actuate the remaining cog-segments, and roller-bearings having the upper end of the vertical shaft journaled therein.

3. In a turbine water-wheel, the combination, with a suitable frame, and a vertical water-motor shaft extending into the frame, of a gear-wheel loosely mounted on the shaft above the frame, a plurality of tapering valve-seats, each valve-seat having two oblong openings therein opposite each other, a plurality of tapering valves adapted to rotate in the valve-seats, each valve having an oblong opening therethrough corresponding to the openings in said valve-seats, a valve-stem mounted on each valve by which the same is adapted to be actuated, a plate rigidly mounted over each valve and valve-seat, concentric cam-rings mounted on the plate, the outer cam-ring being adjustably mounted and having one edge extending beyond the inner cam-ring, the inner cam-ring and the plate having an opening through which the valve-stem extends, other concentric cam-rings, the inner one being rigidly mounted on the valve-stem and the outer one adjustably mounted on the

inner and having its edge extending beyond it, ball-bearings interposed between the inner cam-rings and held in place by the outer cam-rings, a cog-segment rigidly mounted on each 5 valve-stem and adapted to engage the gear-wheel, one cog-segment being adapted to operate the gear-wheel and thereby actuate the remaining cog-segments, and roller-bearings

having the upper end of the shaft journaled therein.

10

In testimony whereof I hereunto affix my signature in presence of two witnesses.

OBED HAND NORDSTROM.
